UNITED STATES PATENT OFFICE.

DANIEL R. BLAKESLEE, OF CORRY, PENNSYLVANIA.

WOOD-SAWING MACHINE.

Application filed March 27, 1924. Serial No. 702,460.

To all whom it may concern:

Be it known that I, DANIEL R. BLAKESLEE, a citizen of the United States, residing at Corry, in the county of Erie and 5 State of Pennsylvania, have invented certain new and useful Improvements in Wood-Sawing Machines; and I do declare the following to be a full, clear, and exact description of the invention, such as will enable others skilled in the art to which it 10 appertains to make and use the same.

My invention relates to motor-driven wood sawing machines and the present disclosure is directed more particularly to a 15 drag saw.

One object of the invention is to provide a simple, inexpensive and practical machine, in which a wheeled axle constitutes a support for the driving engine and the sawing 20 mechanism, and also acts as a drive shaft for the latter.

Another object of the invention is to provide an engine supporting frame which is wheel-supported at one end, the other end 25 of the frame being adapted to support an engine when the machine is in operation, said frame however being of such nature as to permit the engine to be slid into close relation with the supporting wheel or 30 wheels, when the machine is to be drawn from one place to another. Thus, the end of the frame remote from its wheel-supported end, may be easily lifted and if desired connected with a wagon, truck or the 35 like, to be drawn from one place to another.

Another object of the invention is to provide a sawing machine in which the saw-carrying means is pivotal about the supporting axle or drive shaft, so that it may 40 be swung to an inoperative position when the machine is to be moved from one place to another.

A still further aim is to provide novel connecting means between the saw-supporting means and the axle and between the engine-carrying frame and said axle.

Another aim is to provide a unique means for mounting and guiding the saw.

With the foregoing and minor objects in view, the invention resides in the novel subject matter hereinafter described and claimed, the description being supplemented by the accompanying drawings.

Figure 1 is a top plan view of a wood-sawing machine constructed in accordance with my invention.

Figure 2 is a side elevation partly broken away and in section.

Figure 3 is an enlarged horizontal section view as indicated by line 3-3 of 60 Fig. 2.

Figure 4 is a fragmentary elevation illustrating the manner in which the saw is held in a raised position while longitudinally shifting a log beneath said saw. 65

Figure 5 is a detail vertical longitudinal section view showing the mounting and guiding means for the saw.

Figures 6, 7, 8 and 9 are vertical transverse sectional views as indicated by lines 70 6-6, 7-7, 8-8 and 9-9 of Fig. 5.

Figure 10 is a perspective view showing the preferred form of operating crank for the saw and a portion of the co-acting pitman. 75

Figure 11 is a disassembled perspective view showing portions of the saw mounting means.

In the drawings above briefly described, which illustrate the preferred form of my 80 invention, the numeral 1 designates a rotatable axle whose ends are supported by ground wheels 2 and 3, the wheel 2 being formed with an elongated hub 4 whose inner end is preferably provided with a peripheral groove 5. Within this hub, a suitable bushing 6 is preferably provided. The wheel 3 includes a longer hub 7 within which is located a bushing 8, said hub 7 being formed at its inner end with a peripheral 85 groove 9, at its outer end with a similar groove 10, and between the wheel spokes and the groove 9, with a third groove 11. The grooves 5 and 11 are engaged with sectional bearings 12 on the front end of an engine-supporting frame 13, which frame preferably 90 comprises a pair of parallel tracks 14 connected at intervals by appropriate transverse bars 15. The tracks 14 are intended to slidably support the usual skids 16 of an 100 internal combustion engine 17, and this engine drives the shaft or axle 1, through the instrumentality of an appropriate belt 19 and pulleys 20, and obviously, an appropriate clutch may be provided if desired. 105

When the machine is in operation, the engine 17 stands at approximately the rear end of the frame 13, which end may rest on the ground or other adequate support, so that most of the weight of the engine is 110 taken from the wheels and the axle 1. When the entire machine is to be moved

from one place to another however, the engine is slid forwardly into close relation with the axle 1, thus permitting the rear end of the frame 13 to be easily lifted and either 5 moved by hand or connected with a wagon, truck or the like.

I have shown forwardly converging bars 21 and 22 straddling the wheel 3 and provided at their rear ends with bearings 23 10 engaging the grooves 9 and 10 of the hub 7, the front ends of these bars being secured together by any suitable means, such as bolts 24. The bar 22 is preferably provided at its front end with a bolt or other anchor 25 15 for connecting it to a transverse track-way 26 upon which a suitable log carriage 27 may operate, for advancing a log under the saw 28.

I have shown a longitudinal guide rod 29 20 pivoted at its rear end to the bar 22, as indicated at 30, the front end of said rod 29 having an appropriate guide 31 for the saw 28. Slidable upon the rod 29, is a saw carriage, preferably in the form of a tube 32 25 having bushings 33 in its ends, said tube being shown as longitudinally split at 34, so as to permit it to be slightly expanded when removing worn bushings and inserting new ones. Upon the front and rear ends of the 30 tube 32, I have shown pairs of upstanding flanges 35 and 35^a which are clamped together by bolts 36 and 36^a. The flanges 35 are straddled by a pair of upstanding plates 37, between which the rear end of 35 the saw 28 is secured by bolts or the like 38, and the bolts 36 preferably pass through said plates 37 as shown in Fig. 7. Also passing through these plates and through the flanges 35, is a short sleeve 39 which may well be 40 threaded in place, said sleeve receiving a lateral stud 40 on the end of a pitman 41. This pitman is connected with a wrist pin 42 on a balanced crank 43 secured to one end 45 of the axle 1. The crank 43 is preferably, although not necessarily of the type shown.

It will be seen that when the engine 17 is operated, the axle 1 is rotated to operate the crank 43, thus reciprocating the pitman 41 and causing corresponding movement of 50 the carriage 32 and saw 28. Whenever, it is necessary to advance the log beneath the saw, the latter may be raised and held in raised position by the pivoted prop 44, shown more particularly in Figs. 2 and 4, 55 said prop being pivoted at 45, to the bar 22 and being engageable at its upper end with a pin 46 extending laterally from the saw guide 31. When the machine is to be moved from one place to another, the bars 60 21 and 22 and associated parts may be swung rearwardly into compact relation with the frame 13, the engine 17 may be moved to the front end of this frame, and the rear end of the latter may be then easily lifted and 65 manipulated in any desired manner.

Excellent results are obtainable from the details disclosed and they may therefore be followed if desired, but within the scope of the invention as claimed, numerous minor changes may be made.

I claim:

1. A sawing machine comprising an elongated engine-supporting frame, a rotatable axle upon which the front end of said frame is at all times supported, engine-operated means on the frame for driving said axle, a pair of ground wheels having hubs through which said axle passes rotatably, said wheels at all times resting on the ground and having their hubs free of driving connection with the axle, whereby the hub acts as bearings for the axle when the machine is in use, saw-carrying means extending forwardly from and pivotally connected with said axle for vertical swinging, and saw driving means operated by said axle.

2. A sawing machine comprising an elongated engine-supporting frame, a rotatable axle upon which the front end of said frame is supported, the rear end of the frame being adapted to be lifted clear of the ground when the machine is to be transported, an engine on said frame disposed to normally weight said rear end and hold it against the ground when the machine is in use, said engine being movable to a point near said axle when the machine is to be transported, permitting easy lifting of the rear end of the frame, means for driving said axle from said engine, a pair of ground wheels through which said axle passes rotatably, saw-carrying means extending forwardly from said axle, and saw-driving means operated by said axle.

3. A sawing machine comprising a frame, a rotatable axle on which the front end of said frame is supported, the rear end of said frame being adapted to be lifted clear of the ground when the machine is to be transported, said frame including parallel longitudinal tracks along which a saw-driving engine may be slid toward said rear end of the frame to hold it against the ground while the machine is in use or toward said front end of the frame when the machine is to be transported, permitting said rear end to be easily lifted, means for driving said axle from the engine when the latter is on the rear ends of the tracks, a pair of ground wheels through which said axle passes rotatably, saw-carrying means extending forwardly from said axle, and saw-driving means operated by said axle.

4. A sawing machine comprising an elongated frame wheel-supported at one end and adapted to have its other end raised clear of the ground when transporting the machine, sawing means carried by said wheel-supported end of the frame, and a saw-driving engine on said frame normally

disposed at a point remote from the wheel-supported end thereof to weight said other end and hold the same against the ground while the machine is in use, said engine being movable toward said wheel-supported end of the frame when the machine is to be transported, permitting said other end of the frame to be easily lifted.

5. A sawing machine comprising an elongated frame, wheel-supported at one end adapted to have its other end raised clear of the ground when transporting the machine, and sawing means carried by said wheel-supported end of the frame, said 10 frame including longitudinal tracks along which a saw-driving engine may be slid toward said other end of the frame to hold it against the ground while the machine is in use toward said wheel-supported end of the 15 frame when the machine is to be transported, then permitting said other end of the frame to be easily lifted.

6. A sawing machine comprising a ground wheel having an elongated hub, saw-carrying means extending forwardly from said hub and having bearing means in which the same is rotatable, an engine-carrying frame also having bearing means in which said hub is rotatable, a shaft passing rotatably 20 through said hub, means for driving said shaft from the engine on said frame, and saw-operating means driven by said shaft.

7. A sawing machine comprising a ground wheel having an elongated hub formed with 25 a plurality of peripheral grooves, a saw-

carrying frame including bars extending forwardly from said hub and having hub-encircling bearings received in certain of said grooves, an engine-carrying frame having a hub-encircling bearing at its front end 40 received in another of said grooves, a shaft passing rotatably through said hub and adapted to be driven by the engine on said frame, and saw-operating means driven by said shaft.

8. A sawing machine comprising a rotatable axle, a pair of spaced ground wheels having elongated hubs rotatable on said axle, an engine-carrying frame having bearings at its front end encircling said hubs, a 45 saw-carrying frame having bearing means at its rear end encircling at least one of said hubs, means for driving said axle from the engine on said engine-carrying frame, and saw-driving means operated by said axle.

9. A sawing machine comprising a stationary guide rod having a saw guide at its front end, a sleeve reciprocable on said rod and having an upstanding flange, saw clamping plates contacting with opposite sides of 50 said flange and rising therefrom, a bearing sleeve passing through said plates and flange, a pitman having a lateral stud passing through said sleeve, and means for securing said plates against opposite sides of 55 a saw.

In testimony whereof I have hereunto affixed my signature.

DANIEL R. BLAKESLEE.
